UNITED STATES PATENT OFFICE.

HERBERT A. PHILLIPS, OF CLEVELAND, OHIO.

DESIGN FOR A PICTURE AND SERVICE-RECORD FRAME.

52,963.

Specification for Design.

Patented Feb. 4, 1919.

Application filed November 29, 1918. Serial No. 264,740. Term of patent 7 years.

To all whom it may concern:

Be it known that I, HERBERT A. PHILLIPS, a citizen of the United States, residing at Cleveland, in the county of Cuyahoga and State of Ohio, have invented a new, original, and ornamental Design for a Picture and Service-Record Frame, of which the following is a specification, reference being had to the accompanying drawing, forming part thereof.

The figure is a plan view of a picture and service record frame showing my new design.

I claim:

The ornamental design for a picture and service record frame as shown.

HERBERT A. PHILLIPS.
